UNITED STATES PATENT OFFICE.

JOEL T. CASE, OF BRISTOL, CONNECTICUT, ASSIGNOR TO THE NATIONAL
WATER WHEEL COMPANY.

IMPROVEMENT IN WATER-WHEELS.

Specification forming part of Letters Patent No. 108,757, dated November 1, 1870; Reissue No. 1,329, dated April 11, 1871.

DIVISION A.

To all whom it may concern.

Be it known that I, JOEL T. CASE, of Bristol, in the county of Hartford and State of Connecticut, have invented certain new and useful Improvements in Water-Wheels, of which the following is a specification.

My invention consists of the peculiar construction and arrangement of the buckets, as hereinafter described.

In the accompanying drawings, Figure 1 is a side elevation of a wheel of my invention. Fig. 2 is a horizontal section of the same on line x x , and Fig. 3 is a plan view of the under side of the same.

In the manufacture of my invention the wheel, as a whole, (with the exception of its shaft,) will be cast in one piece; but for convenience of description I will refer to it as if made in several parts.

A designates the wheel proper, and B the top plate, to which the buckets a b are secured. These buckets are composed of two parts, C. D. The part C is secured to the top plate, B, in a vertical position, (or nearly so,) and with its outer end curved, as shown at c , so as to form the end of the bucket a , from which point the part C extends inwardly and eccentrically to the wheel A sufficiently far to form the back of two buckets, a b . The part D has one end, d , secured to the top plate, B, and extends downward from said plate far enough to form the end and depth of the bucket b , from which

point its outer edge follows in line with the periphery of the top plate, B, (but gradually descending,) for a distance equal to the length of two buckets, and thus forms the bottom of the buckets a b . The inner edge of the part D is fitted closely to the part C so far as it follows the same. The buckets are thus interlocked until the wheel A is complete. The wheel A is secured to the shaft E, and is designed to be suspended by proper bearings in a vertical position, and incased by a series of chutes in any of the ordinary modes of hanging turbine wheels. The water is discharged from the buckets, as indicated by darts in the several figures. The bucket a discharges directly under the succeeding bucket b , which bucket b discharges from its inside end toward the shaft E. Thus every alternate bucket a b has respectively a bottom and central discharge, while the mouths or inlets of all the buckets are substantially on the same line around the wheel A.

I claim as my invention—

The wheel A with its buckets a b , having respectively a downward and central discharge, and arranged alternately, substantially as described

JOEL T. CASE.
